CLAIM

The ornamental design for an analytical sample detection device, as shown and described.

DESCRIPTION

FIG. 1 is a front perspective view of an embodiment of an analytical sample detection device;

FIG. 2 is top plan view of the analytical sample detection device of FIG. 1;

FIG. 3 is a bottom plan view of the analytical sample detection device of FIG. 1;

FIG. 4 is a front elevation view of the analytical sample detection device of FIG. 1;

FIG. 5 is a rear elevation view of the analytical sample detection device of FIG. 1;

FIG. 6 is a left elevation view of the analytical sample detection device of FIG. 1; and,

FIG. 7 is a right elevation view of the analytical sample detection device of FIG. 1.
